T. O. SCHRADER.
LATCH FOR DOORS.
APPLICATION FILED APR. 6, 1917.

1,265,120.

Patented May 7, 1918.

UNITED STATES PATENT OFFICE.

THOMAS O. SCHRADER, OF ALLENTOWN, PENNSYLVANIA, ASSIGNOR TO THE DENT HARDWARE COMPANY, OF FULLERTON, PENNSYLVANIA, A CORPORATION OF PENNSYLVANIA.

LATCH FOR DOORS.

1,265,120.

Specification of Letters Patent.

Patented May 7, 1918.

Application filed April 6, 1917. Serial No. 160,121.

To all whom it may concern:

Be it known that I, THOMAS O. SCHRADER, a citizen of the United States, residing at Allentown, in the county of Lehigh and 5 State of Pennsylvania, have invented certain new and useful Improvements in Latches for Doors, of which the following is a specification.

My invention has relation to a latch for 10 closing refrigerator doors among other types of doors; and in such connection it relates to the particular constructive arrangement of the same.

The principal objects of my invention are 15 first, to provide a latch with a bolt and an operating lever-handle to latch the door in either the raised or lowered position of the handle by manual pressure exerted against the door or simply slamming the same to thereby cause the bolt to snap into engagement 20 with a keeper therefor; second to provide a latch in which the coiled spring thereof in the compressed condition of the same firmly holds the bolt of the latch so that by 25 pressure exerted manually against the door the spring in expanding, will automatically cause the latch bolt to snap into engagement with the keeper, to thus securely lock the door; and third, to provide a latch arranged 30 so that the coiled spring thereof in the event of the spring becoming disarranged or broken, the operating lever-handle of the latch can be manipulated to either release or engage the latch bolt from or with the 35 keeper to thus instantly open or close the door.

The nature and scope as well as characteristic features of my invention will be more 40 fully understood from the following description taken in connection with the accompanying drawings forming part hereof, in which—

Figure 1, is a front elevational view of a latch for a door, embodying the salient features of my invention.

Fig. 2, is a vertical sectional view through the incasement for a latch for a door of my said invention, showing the detail arrangement thereof.

Fig. 3, is a side elevational view partly in broken section, showing the latching member extending through a slotted wall of the incasement therefor and the integral cam of the latching member and the coiled spring, the latter shown in an expanded con-

dition and the operating lever-handle for manipulating the said cam to thereby position the said latch, for the locking of the door.

Fig. 4, is a front end view of the incased latch, with the operating lever-handle, the 60 latching member being shown in a shifted condition with the operating lever handle elevated, whereby upon pressure exerted against or slamming of the door the latch will snap under the keeper-head in the manner for example, as shown in Fig. 1.

Fig. 5, is a rear elevational view of the internal arrangement of the latching element and operating lever-handle.

Fig. 6, is a similar view of a slightly modified form of the operating lever-handle and latching member cam, in this instance provided with a recess for engaging the lug of said handle therein, for shifting said member; and

Fig. 7 is a side elevational view of the keeper, for the latching member.

Referring to the drawings *a*, is a door and *a*¹, a door frame surrounding the same. The frame *a*¹, is provided with a keeper *a*², having an inclining offset head *a*³, and a rear projection forming a stop or rest *a*⁴, for purposes to be presently explained. *b*, is an incasement provided with end base seats *b*¹ and *b*², for securing the same to the door *a*. 80 The incasement is provided with a front oblong vertical slot *b*², and with a semi-circular slot *b*³, in one of the side walls of the said incasement *b*, both of which slots are provided for purposes to be presently 90 fully explained. The latching member *b*⁴, projects through the semi-circular slot *b*³, and is provided with a cam *b*⁵, movably mounted on a spindle or pin *b*⁶, fixed to the side walls of the casing *b*, as clearly shown 95 in Fig. 5. To the forked portion of the cam *b*⁵, is pivoted a slotted connecting rod *b*⁷, carrying thereon a coiled spring *c*; the opposite end of said rod is mounted on a rear spindle or pin *b*⁸, fixed to the side walls 100 of the casing *b*, as clearly shown in Fig. 5. The coiled spring *c*, abuts at one end against the rear portion of the latch cam *b*⁵, and at the opposite end against the spindle or pin *b*⁸. The operating lever-handle *d*, in its 105 preferable curved form extends through the vertical slot *b*², in the front of the casing *b*, and which lever-handle is operable to revolve partially the cam *b*⁵, to thereby actuate the latching member *b*⁴, in the slot *b*³, 110

110

as clearly shown in Fig. 1. The lever-handle d , is connected with the latch cam b^5 , by means of a link b^9 , for positively actuating the same and thus to provide a range of movement in substantially the arc of a circle through the slot b^8 , of the incasement b , to permit of the setting and holding of the said member to the rear rest a^4 of the keeper-head for while in such position by slamming 10 or pressing the door a , against the frame a^1 , to cause the latching-member under compression of the spring c , to be released and snap in a forward direction from the said rest a^4 , beneath the head a^3 , of the keeper a^2 . 15 The latching-member as thus arranged can be manipulated for locking the door in either the lifted or lowered position of the handle d . Furthermore the latch-cam spring b^5 , in its expanded position with the latching member b^4 , engaged by the head a^3 , of the keeper a^2 , will hold the door a , in a 20 tightly closed condition against the frame a^1 .

The operating lever-handle d , is arranged as shown in Fig. 5, spanning the pin 25 or spindle b^8 , and on which the latch-cam b^5 , is movably mounted. The extension of the handle d , is held in required alining relationship on the rear spindle or pin b^8 , by means of a collar b^{10} , applied thereto, as 30 clearly shown in Fig. 5. This handle is so arranged as to be adapted to release the latching member from its engagement with the keeper-head a^3 , whether the cam spring is in a good working condition or not, by simply actuating the same in an upward direction which opens the door a ; moreover, it is adapted due to its arrangement to force the door into an open position should the door 35 become swollen or tightened from any cause, 40 by simply manipulating the same, in a vertical direction.

The latch of Fig. 6 in constructive arrangement is the same as hereinbefore described, save that the latch-cam in this instance is formed with a deep recess b^{11} , and the operating lever-handle d , is provided with a side lug d^1 , for engaging in said recess for thereby operating said cam and

shifting the latching member an integral part of the said cam. In all other respects the latch is the same as illustrated in Figs. 1 to 5 inclusive.

Having described the nature and objects of my invention, what I claim as new and desire to secure by Letters Patent is:—

1. The combination, in a latch, of a keeper and a cam having a bolt formed therewith and engaging said keeper, a cross-pin, a rod mounted on said pin and connected with said cam, an operating lever-handle 60 pivotally connected with said pin and a link connected with said handle and cam opposite the position of the bolt of said cam, substantially as and for the purposes described.

2. The combination in a latch, of a keeper and a cam having a bolt arranged to engage said keeper, a cross-pin, a rod slidably mounted on said pin and connected with said cam, a spring mounted on said rod, the terminals whereof respectively, bear against said pin and cam, an operating lever-handle pivotally connected with said pin and a link connected with said handle and cam opposite the position of the bolt of said cam, 70 substantially as and for the purposes described.

3. The combination, in a latch, of a keeper and a cam having a bolt arranged to engage said keeper, said cam provided with a recess, 80 a cross-pin, a rod mounted on said pin and connected with said cam, a spring mounted on said rod, the terminals whereof respectively, bear against said pin and cam, an operating lever-handle having a lug arranged to engage the recess of said cam, and said handle pivotally connected with said pin, substantially as and for the purposes described.

In witness whereof, I have hereunto set 90 my signature in the presence of two subscribing witnesses.

THOS. O. SCHRADER.

Witnesses:

MABEL G. DAVIS,
ELSIE V. LICHTY.
